SEAR FOR FIREARMS

Frederick L. Humeston, Syracuse, N. Y., assignor
to The High Standard Manufacturing Corporation,
New Haven, Conn., a corporation of Connecticut

Application November 27, 1943, Serial No. 511,938

3 Claims.

(Cl. 42—69)

The present invention relates to improvements in sears for firearms and relates more particularly to sears composed of sheet metal.

It is known that it has heretofore been proposed to provide sheet-metal sears for firearms but all such prior sheet-metal sears have been open to serious objections, mainly with respect to their inability to withstand continuous usage and particularly the continuous and rough usage to which sears of military firearms are subjected.

The main object of the present invention is to provide a superior sheet-metal sear which combines low cost with adequate strength to withstand long periods of continuous and hard usage.

Another object of the present invention is to provide a superior sheet-metal sear having an integral sear-nose supported by the remainder of the sheet-metal structure in such manner as to effectively withstand severe usage without derangement or distortion.

With the above and other objects in view, as will appear to those skilled in the art from the present disclosure, this invention includes all features in the said disclosure which are novel over the prior art.

In the accompanying drawing, in which certain modes of carrying out the present invention are shown for illustrative purposes:

Fig. 1 is a broken view partly in side elevation and partly in vertical central-longitudinal section of the central portion of a bolt-action military rifle and showing a sheet-metal sear of the present invention incorporated therein;

Fig. 2 is a top or plan view of the sear;

Fig. 3 is a view thereof in side elevation;

Fig. 4 is a view looking toward the rear end of the sear;

Fig. 5 is a view looking toward the forward end of the sear;

Fig. 6 is a transverse sectional view taken on the line 6—6 of Fig. 3; and

Fig. 7 is a perspective view of the sear.

In Fig. 1 is shown portions of a bolt-action military rifle which include a receiver 10, a breech-bolt 11, and a firing-pin 12 axially movable in the said breech-bolt. The said firing-pin 12 is provided at its rear end with a knurled finger-piece 13 by means of which it may be manually cocked and is also provided with a depending cocking-lug 14 formed with a forwardly facing cocking-abutment 15.

The receiver 10 is attached to the upper portion of a stock 16 and is formed at a point below the rear portion of the breech-bolt 11 and firing-pin 12 with a recess 17 in which is accommodated

a sheet-metal sear generally designated by the reference character 18 and which will be more fully hereinafter described. The stock 16 is formed with a vertical clearance-passage 19 registering at its upper end with the recess 17 and communicating at its lower end with a clearance-opening 20 formed in a trigger-plate unit 21 secured in any suitable manner to the underside of the stock 16. The said trigger-plate unit 21 includes a loop-like trigger-guard 22 in which moves a finger-piece 23 formed at the lower end of a trigger 24.

The trigger 24 extends upwardly through a clearance-opening 25 formed in the bottom-wall 26 of the sear 18, as is shown in Fig. 1. In addition to its said bottom-wall 26, the sear 18 includes two laterally-spaced-apart parallel integral side-walls 27—27 and an upwardly-and-rearwardly-curved rear-wall or end-wall 28 integral with and merging into the bottom-wall 26 before referred to.

The bottom-wall 26 of the sear 18 is depressed below the general level thereof at the forward end of the sear to provide an upwardly-facing sear-spring seat 29. Centrally upstanding from the sear-spring seat 29 and riveted at its lower end into the adjacent portion of the bottom-wall 26, is a sear-spring post 30 over which fits the lower end of a helical sear-spring 31. The upper end of the sear-spring 31 thrusts against the adjacent portion of the underside of the receiver 10 and exerts a constant-but-yielding effort to turn the sear 18 in a clockwise direction, as viewed in Fig. 1.

35 Adjacent their respective forward ends, each of the respective opposite side-walls 27—27 of the sear 18 is provided with a vertically-extending mounting-ear 32 formed with a sear-pin hole 33 arranged in alignment with the similar sear-spring hole 33 in the mounting-ear 32 of the opposite side-wall 27, as is especially well shown in Fig. 7.

40 Formed integral with and projecting upwardly from the upper end of the arcuate rear-wall 28 of the sear 18 is a sear-nose 34. As will be seen by reference to the drawing, the sear-nose 34 projects above the respective upper edges of the complementary side-walls 27—27 of the sear 18, and the rear face of the said sear-nose is adapted to engage with the cocking-abutment 15 of the firing-pin 12, as is shown in Fig. 1. Projecting centrally forwardly from the rear portion of the sear 18, partly from the sear-nose 34 and partly 45 from the arcuate rear-wall 28, is an integral

buttress-rib 35 serving to buttress or support the sear-nose 34.

About midway lengthwise of the sear 18, between the sear-nose 34 and the complementary mounting-ears 32-32, each of the side-walls 27-27 is formed with a trigger-pin hole 36 arranged in axial alignment with the similar trigger-pin hole 36 in the other of the two side-walls 27-27. Extending through the two aligned trigger-pin holes 36-36 just referred to and through the upper portion of the trigger 24, is a trigger-pin 37 serving to pivotally connect the said trigger to the sear 18, as is shown in Fig. 1. As will be observed by reference to the figure just referred to, the upper end of the trigger 24 is formed with a fulcrum-boss 38 which is adapted to rock against the under-face of a transverse wall 39 forming an integral feature of the receiver 10 and constituting the major portion of the top-wall of the recess 11 therein.

The sear-nose 34 of the sear 18 normally projects upwardly from the recess 11 in the receiver 10, through a vertical clearance-passage 40 formed in the rear portion of the transverse wall 39 just above referred to. For the purpose of pivotally connecting the sear 18 to the under portion of the receiver 10, a transverse sear-pin 41 is employed which extends through the aligned sear-pin holes 33-33, as is shown in Fig. 1.

As before pointed out, the helical sear-spring 31 exerts a constant-but-yielding effort to swing the sear 18 in a clockwise direction, as viewed in Fig. 1. Thus, the said sear-spring 31 serves to yieldingly urge the sear-nose 34 upwardly for interposition into the path of forward movement of the cocking-lug 14 of the firing-pin 12 and of its cocking-abutment 15.

When the firing-pin 12 is cocked, as shown in Fig. 1, the sear-nose 34 of the sear 18 will serve to releasably hold the firing-pin in such position. If, now, the finger-piece 23 of the trigger 24 is pulled rearwardly, the fulcrum-boss 38 at the top of the said trigger will rock upon the under-face of the transverse wall 39 of the receiver 10, and through the intermediary of the trigger-pin 37 will cause the sear to be turned in a counter-clockwise direction. When the sear is turned as just referred to, the sear-nose 34 will be swung downwardly and eventually will ride free of the cocking-abutment 15 and thereby permit the firing-pin 12 to effect the discharge of the firearm in a manner well known in the art.

It is to be noted that the sear 18 is not merely folded up from sheet metal but, in effect, is cupped up or drawn up from sheet metal so that the respective opposite side-edges of the so-called "rear" wall 28 are integrally united with both of the opposite side-walls 27-27 of the sear 18. The buttress-rib 35, due to its inclination and integrality, serves to so reinforce the sear-nose 34 as to enable the same to withstand the severe usage to which it may be subjected, especially in the event of its employment in a military firearm. The sheet-metal sear may be given an all-over heat-treatment and if desired, the sear-nose 34 may be especially well case-hardened.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

10 I claim:

1. A drawn sheet-metal sear for firearms, including in combination: a bottom-wall; a pair of laterally-spaced-apart side-walls integral with and extending upwardly from the said bottom-wall, the said side-walls being provided with means for pivotally connecting the sear to a firearm-structure; an end-wall integral with the said bottom-wall and integrally united substantially throughout its length to both of the said side-walls, the said end-wall being provided with an integral sear-nose constructed and arranged to releasably engage with the firing-member of a firearm; and an integral buttress-rib connecting the said sear-nose and the said end-wall and formed integral with both thereof.

2. A drawn sheet-metal sear for firearms, including in combination: a bottom-wall; a pair of laterally-spaced-apart side-walls integral with and extending upwardly from the said bottom-wall, the said side-walls being provided with means for pivotally connecting the sear to a firearm-structure; a rear-wall integral with the said bottom-wall and integrally united substantially throughout its length to both of the said side-walls, the said rear-wall being inclined rearwardly and upwardly from the said bottom-wall and provided with an integral sear-nose constructed and arranged to releasably engage with the firing-member of a firearm; and a rearwardly-and-upwardly-inclined integral buttress-rib integrally uniting the said sear-nose and the said inclined rear-wall of the sear.

3. A drawn sheet-metal sear for firearms, including in combination: a bottom-wall; a pair of laterally-spaced-apart side-walls integral with and extending upwardly from the said bottom-wall, the said side-walls being provided with means for pivotally connecting the sear to a firearm-structure; a rear-wall integral with the said bottom-wall and integrally united substantially throughout its length to both of the said side-walls, the said rear-wall being inclined rearwardly and upwardly from the said bottom-wall and having a concave upper forward face and a convex lower rearward face; an integral substantially-vertical sear-nose extending upwardly from the upper rear-terminus of the said inclined rear-wall to releasably engage with the firing-member of a firearm; and a rearwardly-and-upwardly-inclined integral buttress-rib offsetting partly from the forward-face of the said substantially-vertical sear-nose and partly from the inclined concave forward upper-surface of the said end-wall.

65 FREDERICK L. HUMESTON.
